The ornamental design for a controller charging holder, as shown and described.

DESCRIPTION

FIG. 1 is a first perspective view of a controller charging holder showing our design;

FIG. 2 is a second perspective view of FIG. 1;

FIG. 3 is a third perspective view of FIG. 1;

FIG. 4 is a front elevational view of FIG. 1;

FIG. 5 is a rear elevational view of FIG. 1;

FIG. 6 is a left side elevational view of FIG. 1;

FIG. 7 is a right side elevational view of FIG. 1;

FIG. 8 is a top plan view of FIG. 1; and,

FIG. 9 is a bottom plan view of FIG. 1.

The broken lines in the figures represent portions of the controller charging holder which form no part of the claimed design.
